(57) **CLAIM**

The ornamental design for a storage container, as shown and described.

DESCRIPTION

FIG. 1 is a bottom perspective view of my design for a storage container;

FIG. 2 is a top perspective view thereof;

FIG. 3 is a front view thereof;

FIG. 4 is a bottom view thereof; and,

FIG. 5 is a top view thereof.

The back side, left side and right side are identical to the front side.

The broken lines in the drawings represent portions of the storage container that form no part of the claimed design.
